UNITED STATES PATENT OFFICE.

ERNEST LAEUBLI, OF MILWAUKEE, WISCONSIN.

INJECTOR FOR OIL ENGINES.

Application filed July 18, 1923. Serial No. 652,459.

To all whom it may concern:

Be it known that I, ERNEST LAEUBLI, a citizen of Switzerland, and a resident of Milwaukee, in the county of Milwaukee and 5 State of Wisconsin, have invented a new and Improved Injector for Oil Engines, of which the following is a full, clear, and exact description.

The present invention relates to new and 10 useful improvements in internal combustion motors, and it pertains more particularly to oil-burning motors commonly known as Diesel or semi-Diesel type.

It is one of the primary objects of the invention to provide a new and improved form 15 of nozzle for internal combustion motors of the heavy oil-burning type.

It is a further object of the invention to provide a new and improved form of combustion chamber for motors of this type.

It is a further object of the invention to provide a nozzle which will permit of the use of fuel oil of the lowest grade in motors 20 of either the two-cycle or four-cycle internal combustion type.

It is a further object of the invention to provide a nozzle for motors of the aforementioned type in which a complete consumption of the fuel oil is had and a resultant complete combustion is obtained.

It is a further object of the invention to construct the nozzle in such a manner that the oil injected thereby ignites immediately after leaving the nozzle to provide primary ignition, said nozzle storing heat for the purpose of promoting the secondary ignition.

With the above and other objects in view, reference is had to the accompanying drawings, in which

Figure 1 is a detail sectional view of the upper portion of an internal combustion motor cylinder constructed in accordance with the present invention and showing the induction nozzle in position therein;

Fig. 2 is an enlarged detail sectional view showing the nozzle in longitudinal section;

Fig. 3 is a bottom plan view of the nozzle shown in Figs. 1 and 2;

Fig. 4 is a detail view of the nozzle per se, 50 said nozzle being shown both in plan and in section in this figure;

Fig. 5 is a detail sectional view of a slightly modified form of nozzle;

Fig. 6 is a plan view of that form of nozzle shown in section in Fig. 5;

Fig. 7 is a plan view of a still modified form of the invention.

Referring to the drawings and more particularly to Figs. 1 to 4, inclusive, the reference character 10 designates the motor cylinder, and 11 designates the head thereof, the piston of the motor being designated by the reference character 12. The motor head 11 is formed with a globe-shaped chamber 13, 60 and leading from the chamber through the top wall of the head, there is a passage 14, 65 which is adapted to receive an inductor or nozzle 15.

Referring to Fig. 2, it will be seen that 70 the nozzle comprises a body portion 16, of a diameter substantially equal to the diameter of the passage 14 heretofore mentioned. This body portion 16 is provided with a flange 17, which is adapted to engage the 75 top face of the head 11 of the motor cylinder, when the body portion 16 of the nozzle is inserted in the passage 14. The body of the nozzle is adapted to be secured in position on the head of the cylinder by a plate, 80 18, or the like, and said plate is in turn secured to the head of the cylinder by cap screws, bolts, or the like, 19.

Extending longitudinally through the body 16 of the nozzle, is a passage 20, and 85 communicating with said passage 20 and leading into the outer end of the body portion 16 of the nozzle is a fuel pipe 21, which fuel pipe is adapted to be connected to a high pressure oil pump which serves to force 90 the oil through the nozzle 15. The inner end of the body portion 16 of the nozzle is provided with a screw-threaded recess 22, and having threaded engagement with the

screw-threaded recess 22, is a hood member 23. This hood member 23 is cylindrical in form and is provided in its side walls with a plurality of openings 24, preferably circular in form. In the preferred form of the invention the lower end of the hood member is provided with an elongated slot or passage 25, more clearly shown in Fig. 3.

The body portion 16 of the nozzle is provided within the screw-threaded recess 22 with an internally screw-threaded projecting portion 26, and having threaded engagement with the screw-threaded projecting portion 26, there is a cap or shell 27, which serves to retain the nozzle member 28 in position upon the screw-threaded extremity 26. Interposed between the end of the screw-threaded member 26 and the cap member 27, there is a gasket 29.

Referring to Fig. 4, it will be noted that the nozzle member 28 is formed with a flange 30 and a projecting portion 31. This nozzle member is also provided with a recess 32, in which the gasket 29 heretofore mentioned, is adapted to seat, and a chamber 33 is also formed in the nozzle member 30. Leading from the chamber 33, through the body portion 31 of the nozzle, is a plurality of passages 34, preferably arranged in a straight line, as more clearly shown in the plan view of Fig. 4. These passages 34 are so arranged that as the oil is projected therethrough, a spray will be formed and the dimension of said spray will be equal to the longitudinal dimension of the elongated slot 25 in the hood member 23. By this construction it is apparent that the spray of fluid oil will pass through the elongated slot 25.

Positioned upon the lower end of the hood member 23, there is a plate 23', secured by rivets or the like, 24'. Passing longitudinally through the body portion 16 of the nozzle, there is a set screw, or the like, 35, and said set screw is adapted to engage the threaded portion of the hood 23 to maintain the same in adjustment by preventing rotation thereof relative to the body 16 of the nozzle 15.

The device operates in the following manner:

The fuel oil is conveyed to the nozzle by means of the pipe 21, which, as heretofore stated, is connected to a suitable pressure pump. As the spray enters the hood 23, the outside particles ignite immediately after leaving the nozzle by coming in contact with the high temperature within my apparatus, causing primary ignition. By passing the opening in cover all other oil particles will be ignited by touching the hot edges of said opening and cause the secondary ignition and a complete combustion of the fuel within the globe-shaped combustion chamber 13 and furnish the working pressure on the piston.

In that form of the invention shown in Figs. 5 and 6, the hood 23 is formed with a centrally disposed circular opening 40 in its bottom wall in lieu of the elongated slot 25 employed in the preferred form of the invention. This circular opening is reinforced by a flange 41, and the openings 24 are likewise reinforced by a flange 45. This flange 45 while not shown in the preferred form of the invention, is intended to be used in connection with the preferred form since it lends strength to the body of the hood at the openings 24. The nozzle member in the form of the invention shown in Figs. 5 and 6 is provided with a plurality of openings 46, which openings are arranged in a square rather than in a straight line as described in the preferred form of the invention, and these openings are so positioned with respect to each other and with respect to the opening 40 in the hood 23, that the spray emitted by the openings will pass through the opening 40, as shown by the dot-and-dash lines in Fig. 5.

In that form of the invention shown in Fig. 7, the hood 23 is formed in its bottom wall 50 with a plurality of circular openings 51, each of which is bounded by a flange 52, which forms a reinforcement therefor. As shown in dotted lines in this figure, the nozzle has openings 54 in the same relative position as the openings 46 in the form shown in Fig. 6. In the form shown in Fig. 7, the fuel oil is ejected through the openings 54 and pass through the openings 51, in lieu of an elongated slot 25, or a single opening 40, as shown in Figs. 3 and 5 and 6, respectively. In the modified form of the invention the operation is the same as that described in the preferred form of the invention, and, therefore, is not repeated at this time.

From the foregoing it is apparent that the present invention provides a new and improved type of injecting nozzle for oil engines of the Diesel or semi-Diesel type, and that by use of the improved nozzle especially in combination with a globe-shaped combustion chamber, a complete combustion of the fuel is had.

What is claimed is:

1. An injector for internal combustion motors, comprising a body portion formed on its inner end with a circumferential channel providing an internally screw-threaded recess and an exteriorly screw-threaded projecting nipple, a perforated washer adapted for engagement with the end of the nipple, a cap having threaded engagement with said nipple and serving to secure the washer in place in engagement therewith, and a hood member adapted to enclose the nipple and the cap, said hood member having removable threaded engagement with the interiorly screw-threaded recess.

2. An injector for internal combustion motors, comprising a body portion formed on its inner end with a circumferential channel providing an internally screw-threaded recess and an exteriorly screw-threaded projecting nipple, a perforated washer adapted for engagement with the end of the nipple, a cap having threaded engagement with said nipple and serving to secure the washer in place in engagement therewith, and a hood member adapted to enclose the nipple and the cap, said hood member having openings therein in alinement with the perforations in said perforated washer. 10

ERNEST LAEUBLI.
